UNITED STATES PATENT OFFICE.

HEINRICH BOCKISCH, OF POUGHKEEPSIE, NEW YORK, ASSIGNOR TO M. WELTE & SONS,
OF NEW YORK, N. Y., A CORPORATION OF NEW YORK.

AUTOMATIC MUSICAL INSTRUMENT.

1,197,573.

Specification of Letters Patent.

Patented Sept. 5, 1916.

Application filed November 8, 1915. Serial No. 60,391.

To all whom it may concern:

Be it known that I, HEINRICH BOCKISCH, a subject of the Emperor of Austria-Hungary, residing at Poughkeepsie, in the county 5 of Dutchess and State of New York, have invented certain new and useful Improvements in Automatic Musical Instruments, of which the following is a specification.

This invention has relation to record controlled musical instruments of the kind, generally, wherein the production of the tones is controlled by the opening and closing of a series of tone-ducts by a properly prepared operating device or record, and particularly, to those automatic musical instruments—such as organs, orchestrions and the like—whose tone-emitting elements are formed to give forth musical tones when subjected to the influence of currents of air.

20 The invention is illustrated as being applied to a pipe organ operated automatically by means which include a perforated music roll or note sheet as the operating element or record, but this is merely exemplary, 25 the invention being applicable to other musical instruments than pipe organs and being adapted for use with other operating elements or records than a perforated music roll.

30 More particularly the invention has reference to organs, orchestrions and other musical instruments of similar character in which there is generally a very extensive scale or range of note-emitting elements 35 which are sounded in an infinite variety of combinations in the rendition of musical compositions. Citing a pipe organ as an example, the scale runs from very low notes in the pedal to high notes in a manual, or in

40 a plurality of manuals. In order that musical compositions may be correctly rendered, it is necessary that the pedal scale may be played independently of the manual scale and that when more than one manual scale

45 is employed, they may be played independently of each other and of the pedal scale. This permits, for example, the playing of a chord on a very soft stop—as violin, for instance—on the first manual, while at the 50 same time a solo in a different tone color—as oboe—is being played on the second manual and a very deep soft note on a 16 foot bourdon is being played in the pedal. The provision of each manual and pedal scale 55 with a separate series of tone-ducts would

necessitate a great number of such ducts and the operating element or record for opening and closing the ducts would have to be correspondingly wide, if it be a perforated note sheet, or long, if it be a cylinder with projections. The objections to the use of either a very wide note sheet or of a long cylinder are apparent and need not be enlarged upon.

One of the important purposes of the present invention, therefore is to provide an 60 automatic musical instrument with mechanism whereby a plurality of tone-emitting elements may be controlled from a common tone-duct, thereby reducing the size of the operating element or record which otherwise would be required, the said mechanism 65 being of a selective nature such that either of the tone-emitting elements controlled from the common duct may be sounded alone or they may be sounded together, at 70 will, the selective nature of the mechanism being further such that the tones of the two scales may be emitted in an infinite variety of combinations or, in other words, does not 75 in any wise reduce the combinations which 80 would be obtainable if each note-emitting element were provided with a separate tone-duct.

In accordance with this stated purpose of the invention I have provided an automatic 85 musical instrument which comprises, generically, two series of tone-emitting elements (one for manual scale or effects and the other for pedal scale or effects, for example) a series of tone-ducts common to the two 90 series of tone-emitting elements, and a selecting mechanism of a suitable nature arranged to bring any one or more of the elements of one series of tone-emitting elements and any one or more of the elements of the 95 other series of tone-emitting elements into communication with the corresponding tone-ducts independently of every other of the elements of both of said series.

The invention also has other purposes 100 having reference particularly to its embodiment in most practicable and advantageous form, and which will be fully apparent to those familiar with the embodiment thereof hereinafter set forth and skilled in the art 105 to which it relates.

I have selected for illustration herein a most beneficial application and the preferred embodiment of the invention, and while I may herein describe the same with particu- 110

larity, yet I would have it understood that the invention may be otherwise and variously embodied and employed without departing from its spirit or the scope of the 5 subjoined claims. In this particular embodiment of the invention I have considered the instrument as having two series of tone-emitting elements, one of said series being for the manual scale or effects—for instance—and the other for the pedal scale or effects—for example—but it will be understood that additional scales may be employed. I have deemed it to be unnecessary to illustrate, or to refer more particularly 10 hereinafter to such additional scales, as the principle of operation is precisely the same whether two scales or more than two scales are employed, and provision for the operation of the scales of tone-emitting elements 15 additional to those hereinafter set forth may readily be supplied by those skilled in the art. For example, when mechanism of the kind hereinafter particularly set forth is employed for a plurality of manual scales 20 in addition to a pedal scale, it will be necessary only to duplicate the mechanism herein set forth for the one manual scale, this duplication including the addition of a control duct and a primary and secondary control 25 pneumatic, and switch members and their associated parts for each additional scale. The operating characteristics of such additional manual or manuals will preferably be similar to those herein described 30 with relation to the pedal, that is to say, the ways to the operating pneumatics of the additional manual or manuals will preferably be closed.

I wish it to be understood that the invention 40 contemplates the employment of any desired number of scales or series of tone-emitting elements and that the reference either to two series of the latter or to a plurality of series, is intended to include two 45 or more such series.

In the accompanying drawings, wherein like characters of reference denote corresponding parts in the several views: Figure 1 is a diagrammatic representation of a desirable 50 form of a mechanism employed for selectively sounding manual and pedal tones of an organ, the parts being shown in the positions they occupy when the manual tones only are being sounded; Fig. 2 is a view partly 55 diagrammatic of a part of the mechanism intended more particularly to show the preferred correlation of certain of the pneumatics in the actual embodiment of the invention, the referred to pneumatics being shown as arranged in a common chest, the valves being shown in the positions occupied 60 when a pedal tone is being sounded; Fig. 3 is an enlarged sectional view of one end of the chest with the valves in the position they occupy when both manual and

pedal tones are being sounded; Fig. 4 is a transverse section on the line 4—4 of Fig. 3; Fig. 5 is a transverse section on the line 5—5 of Fig. 3; Fig. 6 is a diagrammatic representation of parts of the wind chest and operating pneumatics connected therewith, the parts being shown principally in transverse vertical section; Fig. 7 is a view of one end of the manual chest showing the same in horizontal section, and shows also operating pneumatics connected with the stop valves thereof, the line of section being indicated at 7—7 in Fig. 8; Fig. 8 is a longitudinal vertical section on the line 8—8 of Fig. 7 and additionally shows means, diagrammatically, whereby the stop valve operating pneumatics may be operated automatically; Fig. 9 is a diagrammatic representation of a modified form showing an organization of parts whereby there is a more intimate relationship or combination between the primary and subprimary tone pneumatics; Fig. 10 is a detail representation of a perforated note sheet and part of a tracker board, the note sheet having note perforations and control apertures so correlated that certain notes will be sounded in the manual scale only while other notes will be sounded in both the manual and pedal scales; Fig. 11 is a like view of the same parts showing a correlation of note perforations and control apertures such that certain notes will be sounded in the manual scale only and other notes in the pedal scale only; Fig. 12 also is a like view of the same parts but shows a correlation of note perforations and control apertures such that various effects are produced.

A and B, Fig. 6, designate portions of the wind chest for the manual scale and pedal scale respectively. These portions are provided with chambers, marked *a* and *b* respectively, to which the tone-emitting elements C and D are connected. Organ pipes are a desirable form of such tone-emitting elements and hence have been selected to exemplify this particular part of the invention. There are a series of tone-emitting elements connected with each chamber *a* and *b*, each element giving forth different tones of like quality. While this is particularly shown, in Figs. 7 and 8, with reference to the portion A only, yet it will be understood that the two portions A and B are or may be of substantially similar construction and for this reason it is considered to be sufficient only to illustrate one portion in detail. When, as in an organ, orchestrion, or the like, it is desired to embody in the instrument a plurality or series 110 of tone-producing elements, giving forth different qualities of tone of the same note, it is preferred, as is usual in organs, to provide each portion A and B of the wind chest with a plurality of chambers corre- 115 120 125 130

sponding in number with the number of the qualities of tone which are to be produced. To exemplify this, the portion A of the wind chest appropriated to the manual notes or effects is shown as having two chambers, a' and a^2 , in addition to the chamber a , and each of said chambers, in practice, has connection with a series of tone-emitting elements (C' and C²) which are 5 preferably so formed and arranged that those which emit different qualities of tone of the same note will be in the same transverse line with each other but connected to the different chambers, as shown. Similarly, 10 the portion B of the wind chest appropriated to the pedal notes or effects is, for the sake of example, illustrated as having two chambers, b and b' , provided with two 15 lines of tone-emitting elements (D and D') of different qualities of tone. The same 20 lineal arrangement of the elements giving forth different qualities of tones of the same notes, explained with reference to the portion A, is illustrated with respect to the portion B.

The connection between each chamber and the tone-emitting elements associated therewith includes a valve of any suitable style for each tone-emitting element. Each valve 30 is marked 10 in the accompanying drawings. These valves open and close passages 11 between the chambers and the respective tone-emitting elements. The valves of the elements emitting different qualities of tone of 35 the same note are connected with each other, preferably by rods, 12, as shown, having springs, 13, for closing the valves. A mechanism hereinafter described is provided for opening the valves against the action of 40 these springs.

The chambers a , a' , a^2 , b , b' are connected with a suitable source of supply of air under pressure and have valves, 14, suitably operated to admit the air to the respective 45 chambers. In the ordinary humanly played organ, these valves 14 are connected with the stops of the organ. In the present instance, they are operated automatically, but the particular means for this purpose forms 50 no essential part of the present invention. In Figs. 7 and 8 I have exemplified a suitable arrangement, wherein the wind chest has a pressure chamber 15 which is tapped by openings 16 leading to the respective 55 chambers, a , a' and a^2 . It will be understood that a similar arrangement obtains with respect to the chambers b and b' . These openings are controlled by the valves, 14, respectively, which are connected by 60 rods 17 to the movable spring-pressed boards 18^a of the bellows 18 which respectively are provided with ducts 19 having connection through a suitable pneumatic 19^b and ducts 19^c with special apertures 19^a in 65 a tracker-board E, when a tracker-board is

employed. In this exemplified form of the invention the pneumatic 19^b is provided also with a suction duct 19^d.

The several tone-ducts are designated 20. These ducts have connection with the valves 70 10 through intervening mechanism which forms the essence of the present invention. Their mouths preferably are arranged in the tracker-board E.

For opening and closing the ducts 19 and 75 20 I prefer to use a perforated music roll, as shown at E'.

In this invention, certain of the tone-ducts 20 are common to valves 10 of both portions a and b of the wind chest. For example, if 80 the manual chest A has a scale of sixty-one (61) notes and the pedal chest B has a scale of thirty (30) notes additional to those of the manual chest, the ducts 20 for the lower thirty (30) notes of the manual scale 85 will be employed for the pedal scale also, the remaining thirty-one (31) notes of the manual scale having a separate duct for each such note. As this invention is concerned only with the notes having ducts 90 common to a plurality of scales, it is considered to be unnecessary to illustrate or to further refer to provision for causing the sounding of the additional notes which may be embodied in said manual scale. The use 95 of the same tone-duct for controlling manual and pedal notes for example, reduces the number of ducts which otherwise would be required and accordingly reduces the length of the tracker-board and the width 100 of the music roll. As already stated, the invention contemplates additionally a selecting mechanism of such nature that from the same hole or tone duct the tone may be sounded in the manual alone, or in the pedal 105 alone, or in both together, at will, the mechanism further being so arranged that any note of the pedal scale may be sounded simultaneously with any note of the manual scale, so that the manual and pedal notes 110 may be sounded in any of the infinite variety of combinations thereof required by musical compositions.

Referring now particularly to Fig. 1: G designates a "primary tone-pneumatic", as 115 it is hereinafter called. This pneumatic is here shown as comprising a passage 23 on one side of which is a chamber 24 separated from the passage by a flexible membrane 25, and on the other side of which passage there 120 is a chamber 26 having ports 27 and 28 through which it has communication alternately with sources of supply of air of relatively different pressures—as atmospheric or normal and suctional or subnormal, for example. In the chamber 26 there is mounted a valve 29 on a stem 30, the said valve being arranged to open and close the ports 27 and 28 alternately, by movement of the membrane 25 to which its stem 30 is connected. 130

The chamber 24 has communication with the passage 23 through a bleed-hole 31. One of the tone-duets 20 enters this chamber 24. This pneumatic is operated by variations 5 in the difference in pressures of air in the passage 23 and chamber 24 acting upon the membrane 25. This variation of pressure is controlled by the opening and closing of the ducts 20, which, as already stated, 10 may conveniently be effected by the utilization of a properly prepared music roll E' traveling over a tracker-board E. It is preferred to utilize in the passage 23 air at less than atmospheric pressure. For maintaining 15 less than atmospheric pressure in the passage 23 I preferably connect this passage by a pipe 32 with a reservoir H in which a substantially constant suction is maintained by a suitable bellows or pump, 20 not shown. In such case, the port 28 of chamber 26 preferably opens into the atmosphere. Associated with the primary tone-pneumatic G in this particular embodiment of the invention is what I call a "sub- 25 primary tone-pneumatic" G' which comprises a chamber 33 connected with chamber 26 of the primary pneumatic G by a duct 34. The chamber 33 has a membrane 36 to which is connected the stem 37 of a valve 38. 30 The valve 38 is mounted in a chamber 39 and is arranged to alternately open and close ports 40 and 41 which respectively connect the chamber 39 with the chamber 35 and a passage 42. The chamber 35 opens to 35 the atmosphere, as indicated, and the passage 42 has communication through a duct 43 with the constant suction reservoir H.

In practice there is preferably a primary tone-pneumatic G for each tone of the longer 40 scale—the manual scale, for example—and a separate sub-primary tone-pneumatic G' for each tone of the shorter scale—the pedal scale for example. When the primary and sub-primary pneumatics are separated from 45 each other, the primary pneumatics are (see Fig. 2) preferably mounted in a common chest G² which also contains primary control pneumatics L, L' hereinafter described, in which case the passage 23 will be common 50 to the several chambers 24 and 26 of the primary tone pneumatics and also to chambers 89 and 85 of the pneumatics L, L' and said passage 23 will have a single duct 32 leading to the suction reservoir H. The 55 sub-primary pneumatics G' will preferably be arranged in a separate chest K² which also contains pneumatic switches, hereinafter described, as shown in Fig. 2.

The chambers 39 of the sub-primary tone 60 pneumatics G' have connection with operating pneumatics J and J' associated with the manual wind chest and pedal wind chest respectively. These operating pneumatics preferably include expansible and collapsible members, as bellows, 44 and 45, having

connection with the valve rods 12 of the manual chest A and pedal chest B respectively, and also include valved means for controlling the supply of air or other suitable fluid to and its withdrawal from said 70 members. The valved means of the operating pneumatics J and J' may be of identical construction and each preferably comprises a suction passage 46 having a port 47 through which it may have communication 75 with a chamber 48, said chamber 48 having a port 49 leading to the bellows and also having a port 50 opening into an atmospheric passage 51 on one side of which there is a flexible membrane 52 separating the 80 passage 51 from a chamber 53. In the chamber 48 there is a valve 54 having a stem 55 by which it is connected to the membrane 52.

It will be understood that in practice there 85 is one operating pneumatic J for each note of the manual scale and a separate pneumatic J' for each note of the pedal scale, and that the series of pneumatics J and the series of pneumatics J', respectively, are 90 preferably arranged in the form of chests having the several chambers 48 and 53, valves 54 and membranes 52 and provided with common passages 46 and 51.

The operating bellows 44 and 45 are connected with their respective rods 12 preferably by bell crank levers 56 and links 57. In this exemplified form of the invention, the passages 46 of the respective operating pneumatics are under suction, being connected with the suction reservoir H by ducts 58. In the arrangement herein shown the placing of either chamber 53 under suction causes the valve 54 connected with the membrane 52 of said chamber to be moved into position wherein it opens port 47 and closes port 50 whereupon the particular bellows connected with said chamber will be collapsed, causing the sounding of the particular note-emitting element whose valve 10 is 100 connected with said bellows: and, similarly, the placing of any chamber 53 under atmospheric pressure will cause the membrane 52 of said chamber to be moved so as thereby to move the valve connected to said membrane into position wherein it opens chamber 48 to atmospheric chamber 51 and cuts off its communication with the suction chamber 46, whereupon the particular bellows connected with said chamber 48 will be expanded and the valve 10 returned to its closed position, the closing of said valve being assisted by the spring 13 connected with the rod 12.

Included in the suction line between the 125 pneumatics G, G' and the pneumatics J, J' are suitable members K and K' for manual effects and pedal effects respectively and which combine to form what is hereinafter called "pneumatic switch". The switch 130

members K, K' in the particular embodiment selected to exemplify a most practicable form of the invention, include two pairs of connected valves 59 and 60 having operating membranes 69 and 76, 70 and 77 and associated with chambers for air of different pressures, presently described, so coöordinated or combined and connected with the pneumatics J and J' that the latter will be operated in accordance with the positions of the valves of the pneumatic switch, which valves, in turn, are selectively controlled, pneumatically, preferably by the means hereinafter set forth.

Upon reference to Fig. 2 it will be seen that the several pneumatic switches are embodied in a chest K², each switch having for, or as a part of, each pair of members K, K', a common suction chamber 61, a common atmospheric chamber 62, ports 63 and 64 through which the suction chamber and atmospheric chamber have communication with each other, a pair of chambers 65 and 66 arranged on one side of the atmospheric chamber 62, a pair of chambers 67 and 68 arranged on the side of the suction chamber 61 opposite the atmospheric chamber and separated from said suction chamber by flexible membranes 69 and 70, channels 71 and 72 (shown best in Fig. 1) which connect chamber 65 with chamber 67 and chamber 66 with chamber 68, respectively, the said passages respectively having openings 71^a and 72^a into the ports 63 and 64. The chest further has for each pair of switch members K, K' a pair of chambers 73 and 74, and wind passages 75 and 75^a (see Figs. 4 and 5) one of which wind passages is common to all the manual members K and the other common to all the pedal members K', the chambers 73 and 74 of the latter having openings 73^a and 74^a to these passages. The chambers 73 and 74 are separated from the chambers 65 and 66 by flexible membranes 76 and 77. The valves 59 are mounted in the chamber 61 and the valves 60 are mounted in the chamber 62. The valves 59 and 60 of each manual switch member K are mounted on a common stem 78 whose opposite ends are connected to the corresponding membranes 69 and 76 and the like valves 59 and 60 of each pedal switch member K' similarly are mounted on a common stem 79 whose opposite ends are connected to the corresponding membranes 70 and 77.

The chambers 61 of the pneumatic switches are connected with the sub-primary pneumatics G'. It is preferred, as shown in Fig. 2, to incorporate these sub-primary pneumatics in the chest K² and to connect their chambers 39 with the chambers 61 by ducts 80. The passages 71 and 72 of the pneumatic switches are connected with the chambers 53 of the operating pneumatics J and J' respectively by ducts 81.

It will be understood that in practice there is one switch member K for each note of the manual scale and one switch member K' for each note of the pedal scale and that they control the operation of the respective operating pneumatics J and J' by placing the chambers 53 of the latter in communication with air at atmospheric pressure or at less than atmospheric pressure as required, as will be hereinafter more fully explained. 70 They are in turn controlled through the agency of a mechanism which includes primary control pneumatics L and L' for the manual and pedal scales respectively. There need be only one of each of said pneumatics 80 L and L' in the form of the invention herein illustrated and they are preferably operated by special apertures in the perforated music roll E' when such a roll is employed as the operating element for the mechanism. 85 Each may be and preferably is of form substantially similar to the primary tone pneumatics G and are preferably arranged in the chest G² which contains said tone pneumatics, as herein shown. Each has a suction chamber which in the exemplified form of the invention is a part of the suction passage 23 and hence is marked 23 in Figs. 1 and 2. Each control pneumatic L, L' has at one side of the passage 23 a flexible membrane 83 and at the other side of said passage a port 84 leading to a chamber 85 having a port 86 to the atmosphere. In the chamber 85 there is a valve 87 having a stem 88 connected to the membrane 83. The membrane 83 separates the suction passage 23 from chamber 89 and a bleed hole 90 is provided through which the chamber 89 has communication with the passage 23. The chambers 89 are provided with ducts 91 and 92 respectively whose mouths are preferably in the tracker-board E, in the form of special apertures in said board, so that they may be opened by special apertures provided in the perforated music roll when the latter is 100 employed as the operating device for the mechanism. The diagrammatic representation shows branch pipes 93 and 94 leading from the passage 23 and tapping the ducts 32 and 43 respectively, but it will be understood that in practice these pipes need not be used when the control pneumatics are incorporated in the chest G². These primary control pneumatics L and L' respectively have connection with the switch members K 110 and K' through intermediate secondary control pneumatics M and M', of which secondary control pneumatics there need be only one (M) for the entire manual scale and one (M') for the entire pedal scale. In the here- 115 in exemplified form of the invention each pneumatic M and M' comprises a chamber 95 and these chambers have communication with the suction reservoir H through pipes or passages 96 and 97, respectively. Each sec-

120
125
130

ondary control pneumatic also includes a chamber 98 and an atmospheric passage 99, the chamber 98 having ports 100 and 101 between it and the chamber 95 and atmospheric passage, 99, respectively. In each chamber 98 there is a valve 102 for closing its ports 100 and 101, alternately. The valves 102 are mounted on stems 103.

In the herein exemplified form of the invention the mechanism is so arranged that the tones of the manual scale are sounded when both of the special control ducts 91 and 92 are closed, and hence the manual control pneumatic M is provided with a chamber 104 which has a flexible membrane 105 separating it from the passage 99. The chamber 104 has communication with the chamber 85 of the primary control pneumatic L through a duct 106. The membrane 105 is connected to the stem 103 of the valve 102 of the pneumatic M and the chamber 98 of said pneumatic is connected, preferably by a duct 107, with the wind passage 75 of the pneumatic switch chest K². The secondary pedal control pneumatic, M', has its atmospheric passage 99 separated from a chamber 108 by a partition 109 and the chamber 108 has communication with the chamber 85 of the primary control pneumatic L' through a duct 110. Chamber 108 is separated from a chamber 112 by a flexible membrane 113. The membrane 113 is connected to the stem 103 of the valve 102 of this pneumatic M'. Chamber 112 has connection with chamber 95 through a passage 114 and chamber 98 has connection with the wind passage 75^a of the pneumatic switch chest K² through a duct 115.

In the herein illustrated embodiment of the invention the parts are so arranged that the manual tones are not sounded when the special duct 91 is open to the atmosphere: while the pedal tones are sounded only when the special duct 92 is open to the atmosphere. Accordingly, it will be apparent that when both ducts 91 and 92 are open to the atmosphere, the pedal tones connected to the open tone-apertures 20 will be sounded, and when both said special ducts 91 and 92 are closed the manual tones connected to the open tone-apertures 20 will be sounded, and when the special duct 92 is open and the special duct 91 is closed, both pedal tones and manual tones connected to an open tone duct or ducts 20 will be sounded. It will thus be seen that according to this arrangement the manual tones are normally operative and the pedal tones normally silent.

More particularly set forth the operation is as follows:—In Fig. 1 the parts are shown in the positions they occupy when both special control ducts 91 and 92 are closed and a tone-duct 20 is open. It will be noted that the valves 87 of both the primary control pneumatics L, L' are in such position that

the chambers 85 of the latter are closed against the suction passage 23 and open to the atmosphere: the valve 102 of the secondary manual control pneumatic M is in such position that the chamber 98 is open to the atmosphere and closed against the suction chamber 95 whereby the wind passage 75 of the chest K², common to all the manual switch members K, is open to the atmosphere through the channel 99, port 101, chamber 98, and duct 107 of pneumatic M, the valves 59 and 60 of the several members K at this time being so positioned that the ports 63 will be open to the chambers 61. Thus the ports 63, openings 71^a, passages 71 and ducts 81 between the chambers 61 of the pneumatic switches and the several operating pneumatics J are open. The valve 102 of the secondary control pneumatic M', however, is closed against the atmosphere and open to the suction chamber 95 when the valve of the primary operating pneumatic is in the position shown in Fig. 1. Consequently, the wind passage 75^a of the chest K², common to all the pedal switch members K' is under suction and the several valves 59 and 60 of the latter accordingly are in such positions that the ports 64 are closed against the chambers 61 and open to the atmosphere. Hence, the chambers 53 of the pedal operating pneumatics J' have communication with the atmosphere through channels 62, ports 64, openings 72^a, channels 72 and ducts 81. It will now be seen that when any of the tone ducts 20 are opened, and the chambers 24 of the respective primary tone pneumatics G connected therewith are thus opened to the atmosphere, causing the membranes of such pneumatics to be moved, the valves 29 connected with such membranes will be operated to open the chambers 26 of the primary tone pneumatics to the suction passage 23 and to close said chambers against communication with the atmosphere. The chambers 26 being respectively connected with chambers 33 of sub-primary pneumatics G', the latter chambers will be under suction whereupon the valves 38 will be moved to cut off communication of chambers 39 with the atmosphere and open communication of said chambers 39 with the suction passage 42. The particular chamber or chambers 61 connected with the sub-primary pneumatics G' whose valves are in the position shown in Fig. 1, will now be under suction from the latter pneumatics and this suctional force will be communicated through the ports and passages already indicated to the respective chambers 53 of the operating pneumatics J whereupon the valves 54 of the latter will be moved to cut off communication of chambers 48 with the atmosphere and open communication between said chambers 48 and the suction passage 46, thereby collapsing 125

the corresponding bellows 44. Meanwhile, the suctional force in the several chambers 61 which have been thus subjected to such force is not communicated to the chambers 53 of the pedal operating pneumatics J' because the ways between said chambers are closed by the valves 59 of the pedal switch members K' and the ways between the chambers 53 and the atmosphere are opened by 5 the valves 60. Hence manual tones only are sounded when both ducts 91 and 92 are closed, as shown in Fig. 1. When, however, both ducts are open, the manual operating bellows will be unaffected by the opening 10 of any tone-duct and the pedal operating bellows will be collapsed by the opening of their respective tone ducts. Thus when both control ducts 91 and 92 are open, the valves 15 87 of the primary control pneumatics L and L' will be in such position that the chambers 85 of both said pneumatics will be opened to the suction passage 23 and closed 20 against the atmosphere.

The suctional force communicated to chamber 104 of secondary manual control pneumatic M will cause the membrane 105 of said pneumatic to move the valve 102 to such position that it closes the chamber 98 against the atmosphere and opens it to the 25 suction chamber 95: while the suctional force communicated to chamber 108 of secondary pedal control pneumatic M' brings about a balancing of such forces on the membrane 113, whereupon the valve 102 of this 30 pneumatic will move by gravity to the position in which it opens its chamber 98 to the atmosphere and closes it against the suction chamber 95. The wind passage 75 common to the several switch members K is now under suction while wind passage 75^a common 35 to the several switch members K' now contains air at atmospheric pressure, the result being that the several valves 59 and 60 of the pneumatic switches will be in such position 40 that the ports 64 will be open to the chambers 61 and closed against the passage 62 while the ports 63 will be closed to the chambers 61 and open to the passage 62. It will 45 now be seen that the suctional force communicated to any of the chambers 61 by the raising of appropriate valves 38 will have 50 access to the corresponding chambers 53 of pedal operating pneumatics J', whereupon the valves 54 of the latter pneumatics will be raised and the chambers 48 opened to suction 55 passage 46, thus causing the collapsing of the appropriate pedal operating bellows 45.

It will be remembered that the manual 60 tones are emitted when the control duct 91 is closed and passage 75 of chest K² open to the atmosphere, and it will be apparent therefore that if it is desired to cause the emission of both manual and pedal tones it will be 65 necessary only to open the way to the pedal

operating pneumatics J' without closing the way to the manual operated pneumatics J. That is to say, it will be necessary only to open one of the special control ducts, to wit, the duct 92. When this has been done, the 70 chamber 89 of the pedal control pneumatic L' will be opened to the atmosphere, whereupon the valve 87 of the latter will be moved to open communication of chamber 85 with suction passage 23. Chamber 108 of the secondary control pneumatic M' will now be under suction whereupon the valve 102 of the latter pneumatic will move and open chamber 98 to the atmosphere and close said chamber against the suction chamber 95. 80 This places wind passage 75^a in communication with the atmosphere, with the results hereinbefore stated.

It will be seen from the foregoing that the valves 59 and 60 of the pedal switch members K' are normally in such position that the passages from the tone pneumatics G, G' to the respective pedal operating pneumatics J' are closed by the valve 59 and the pedal operating pneumatics are in communication 85 with the atmosphere entering through passage 62. The correlation of parts, however, as to the manual organ, is such that the passages from the tone pneumatics G, G' to the respective manual operating pneumatics J 90 are normally open, the valves 59 being away from the ports 63 and the valves 60 closing said ports to the entrance of atmospheric air through the passage 62. The control duct 91, accordingly, is never open alone and is 100 opened in conjunction with duct 92 when it is desired that the tones of the pedal organ only shall speak, as hereinbefore stated. It will also be seen that when the control duct 92 is opened the valves of all the pedal 105 switch members K' will be shifted from the position shown in Fig. 1 to the position shown in Fig. 2, thereby opening the passages from the tone pneumatics G, G' to the pedal operating pneumatics J' and cutting 110 off the entrance of atmospheric air from the passage 62, and that if the duct 91 be opened at the same time all of the valves of the switch members K will be shifted from the position shown in Fig. 1 to the position 115 shown in Fig. 2. If, however, the control duct 91 be not opened when control duct 92 is opened then the valves of the switch members K will remain in the position shown in Fig. 1, and the valves of all the switch members K' will be in the position shown in Fig. 2. Hence, the passages to the several manual and pedal operating pneumatics J, J' will be opened. The last named position of the valves is shown in Fig. 3.

It will be remembered that when the passages to the manual operating pneumatics J are open the passage 75 of the pneumatic switch chest K² is in communication with the atmosphere through the secondary con- 130

trol pneumatic M and is under suction when the passages to the manual operating pneumatics J are closed: and that when the passages to the pedal operating pneumatics J' are open, the passages 75^a, associated with the pedal switch members K' are open to the atmosphere through the secondary pedal control pneumatic M', and said passage 75^a is under suction when the passages to the 10 pedal operating pneumatics J' are closed. Accordingly, it will be noted that the application of suctional force to any one of the chambers 61 incident to the opening of the corresponding tone duct tends to maintain 15 the valves in their adjusted position due to the correlation of membranes and passages in the pneumatic switches. Thus, with only the passages to the manual operating pneumatics J open and the passages to the pedal 20 operating pneumatics J' closed, the application of suctional force to any one of the chambers 61 will be communicated to corresponding chambers 67 and 65, whereby there is a balancing of forces on opposite 25 sides of the corresponding membrane 69 and suctional force on the underside and atmospheric pressure on the upper side of the corresponding membrane 76, in consequence of which the valves 59 and 60 of the manual 30 switch members K are held down; the application of suctional force to chamber 61 at the same time pulling up on the membrane 70, the underside of which membrane is subjected to atmospheric pressure entering 35 through the port 64 into chamber 68 and at the same time the underside of the membrane 77 is subjected to atmospheric pressure and its upper side to suction, in consequence of which the valves 59 and 60 of the 40 pedal switch member K' are held up. When the position of the valves is reversed, *i. e.*, when the passages to the pedal operating pneumatics J' are open and the passages to the manual operating pneumatics J are 45 closed, the pressures described with relation to the membranes of the manual switch members K are now those of the pedal switch members K' while the pressures previously described with relation to the pedal 50 switch members K' are now those having relation to the manual switch members K, and hence the valves are maintained in their proper adjusted positions. When the 55 passages to the pedal and manual operating pneumatics are open the application of suctional force to any of the chambers 61 incident to the opening of the tone ducts obviously will maintain the valves of the corresponding switch members K, K' in 60 their proper adjusted positions because the suctional force will be communicated to the underside of all of the upper and lower membranes of said members, the upper sides of all of said upper membranes being 65 at the same time under atmospheric pressure

and the upper sides of all said lower membranes being under suction. Thus there can be no movement of the valves, either accidentally or otherwise, in any one of the chambers 61 while said chamber is under 70 suction and hence the opening or closing of control ducts has no effect on tones which at the moment of such opening and closing are being sounded. The opening or closing of the control ducts, however, does effect the 75 adjustment of valves in chambers which are not under suction when said control ducts have been opened or closed. Hence, by the use of a properly prepared operating element it is practicable to sound any note or 80 notes of the pedal scale with any note or notes of the manual scale, without affecting other notes already being played and, similarly, other notes of either pedal or manual scales may be introduced. For example, as 85 exemplified by Figs. 10, 11 and 12, when a perforated music roll is utilized as the operating element, the special perforations 91^a, 92^a which control the ducts 91 and 92 respectively may be arranged to act only in 90 relation to those tones which are controlled by note perforations 20^a whose forward ends are substantially in line with the rear ends of the control apertures: that is to say, only those corresponding tones controlled by the 95 perforations 20^a are sounded simultaneously in both the pedal and manual scales, when the control duct 92 is open and the control duct 91 is closed, as exemplified in Figs. 10 and 100 12, the tones controlled by the other note 105 perforations, 20^b, whether the latter be already in registration with respective tone ducts 20 or later come into registration with ducts while the perforation 20^a is in registration with a duct 20, sounding only in the manual scale; and similarly (as exemplified by Figs. 11 and 12) only those corresponding tones controlled by perforations 20^a are 110 sounded in the pedal scale alone when both control ducts 91 and 92 are open, the tones 115 controlled by the note perforations 20^b sounding only in the manual scale. It will be noted that the production of various effects are exemplified by Fig. 12, namely, the lowest right hand perforation 115 20^b, causes the sounding of a note in the manual alone and just before this is discontinued a chord consisting of six notes in the manual is introduced with two supporting notes in the pedal, the pedal notes corresponding with two of the notes sounding in the manual; this is followed by the discontinuance of five notes of the chord sounding 120 in the manual and one of the corresponding notes of the pedal, the remaining note continuing to sound in both manual and pedal, unaffected by the opening of the two control ducts 91, 92, the opening of said control ducts similarly having no effect with respect 125 to the two notes which are caused to sound 130

by the registration of the two note perforations 20^b in the second line with their respective tone ducts, these two notes hence sounding in the manual alone while the one 5 long note is continuing to sound in both pedal and manual; this in turn is followed by the discontinuance of the long note referred to in both pedal and manual and the introduction at or about the same time of a note in the 10 pedal alone—controlled by said opening of the two ducts 91, 92—while the two notes previously referred to, related to the second line of note perforations are being sounded in the manual alone; this is succeeded by the discontinuance 15 of the manual notes corresponding to the second line of perforations and the introduction of other manual notes alone, corresponding to the third line of perforations, immediately before the sounding of the 20 pedal note corresponding to the second line of note perforations ceases, and while these notes of the manual alone are still sounding an additional note is introduced which sounds in both the pedal and manual and 25 while the latter is sounding another note in the manual only is introduced.

It will be understood of course that the length of the special control apertures should be such—proportional to the speed of 30 travel of the music roll and the inertia of the pneumatic switches and control valves—that these valves will promptly return to their normal positions, as hereinbefore set forth, except such as are associated with 35 particular chambers 61 under suction.

It will therefore be seen that the present invention embodies in combination a series of tone-emitting elements, such as C, producing manual effects, a series of tone-emitting 40 elements, such as D, producing pedal effects, a series of tone ducts, 20, common to the elements of both of said series of tone-emitting elements, and a selecting mechanism illustrated in Figs. 1 and 2 arranged 45 as hereinbefore set forth to bring any one or more of the elements of one of said series of tone-emitting elements and any one or more of the elements of the other of said series into communication with the tone ducts, 50 independently of every other element of both of said series.

It is not altogether essential that the sub-primary pneumatics G' be employed. It is practicable to employ one primary pneumatic alone for each tone and to incorporate 55 these primary pneumatics in the chest K², as indicated in Fig. 9. In this figure, the valve, marked 150, operates precisely as has been described with reference to the pneumatic G, its operation being controlled by the forces imposed on the lower membrane, marked 151. An upper membrane, marked 152, together with a chamber 153, is shown, but the latter membrane and chamber are 60 functionless in this particular embodiment, 65

the pneumatic being shown in this form merely because it is then adapted for use either as a subprimary G', in which case its lower membrane is functionless, or as a primary pneumatic, in which case its upper 70 membrane is functionless, this embodiment being used merely because it avoids the necessity of building the pneumatic differently for each such different use.

It will be understood that while I have 75 arranged and described the parts with reference to the use of air at subnormal or less than atmospheric pressure in conjunction with air at normal or atmospheric pressure, yet this is merely exemplary as it will not be 80 a departure from the spirit of the invention or the scope of the claims to so arrange and coördinate the parts that air of any suitably 85 relatively different pressures may be employed.

Having now described the invention what I believe to be new and desire to secure by Letters Patent, and what I therefore claim, is:—

1. A record-controlled musical instrument 90 comprising, in combination, two series of tone-emitting elements, a series of tone ducts common to the two series of elements and mechanism for selectively controlling communication of the tone ducts with the tone 95 emitting elements, said mechanism including means for bringing any one or more of the elements of one series of tone-emitting elements and any one or more of the elements of the other series of tone-emitting 100 elements into communication with the corresponding tone ducts independently of every other of the elements of both of said series, whereby any one or more tones in either series may be sounded alone, or any 105 one or more tones in one series may be sounded in combination with any one or more of the tones of the other series.

2. A record-controlled musical instrument 110 comprising, in combination, a movable operating element, a series of tone ducts controlled thereby, two series of tone-emitting elements, to which said tone ducts are commonly related, a selective mechanism to bring any one or more of the elements of 115 one of said series and any one or more of the elements of the other of said series into communication with their corresponding common tone ducts independently of every other element of both of said series and 120 means for controlling said selective mechanism from said operating element.

3. A record-controlled musical instrument 125 comprising, in combination, a series of tone-emitting elements producing manual effects, a series of tone-emitting elements producing pedal effects, a series of control ducts common to the elements of each of the aforesaid series and a selecting mechanism to bring any one or more of the elements of 130

- one of said series of tone-emitting elements or any one or more of the elements of the other of said series of tone-emitting elements into communication with their corresponding tone ducts independently of every other element of both of said series whereby any one or more of said tone producing elements in one of said series may be sounded in combination with any one or more of the tone producing elements of the other of said series
4. A record-controlled musical instrument comprising, in combination, a movable operating member, a plurality of tone-ducts controlled thereby, a series of tone-emitting elements producing manual effects, a series of tone-emitting elements producing pedal effects, said tone ducts being common to both of said series of tone-emitting elements, a selective mechanism to bring any one or more of the elements of one of the series of tone-emitting elements and any one or more of the elements of the other of said series into communication with the corresponding common tone ducts, independently of the remaining elements of both of said series and means for controlling said selective mechanism from said operating element.
5. A record-controlled musical instrument comprising, in combination, two series of tone-emitting elements, a series of tone ducts common to the two series of elements, a selecting mechanism to bring any one or more of the elements of one of said series and any one or more of the elements of the other of said series into communication with their corresponding tone ducts independently of every other element of both of said series, a control duct related to said selective mechanism and means for controlling the tone ducts and the control ducts.
6. A record-controlled musical instrument comprising, in combination, a series of tone-emitting elements producing manual effects, a series of tone-emitting elements producing pedal effects, a series of tone-ducts common to both of the aforesaid series of tone-emitting elements, a selecting mechanism co-operatively related to the tone ducts and the tone-emitting elements and establishing communication between any one or more of the elements of one of the series of tone-emitting elements and any one or more of the elements of the other series of tone-emitting elements and the common tone ducts independently of each and every remaining element of both of said series of tone-emitting elements, said selective mechanism comprising a manual control duct and a pedal control duct; and means for opening and closing the control ducts and the tone ducts.
7. A record-controlled musical instrument comprising, in combination, a series of tone-

emitting elements producing manual effects, a series of tone-emitting elements producing pedal effects, a series of tone-ducts common to both of the aforesaid series of tone-emitting elements, a selecting mechanism co-operatively related to the tone ducts and the tone-emitting elements and establishing communication between any one or more of the elements of one of the series of tone-emitting elements and any one or more of the elements of the other series of tone-emitting elements and the common tone ducts independently of each and every remaining element of both of said series of tone-emitting elements, said selective mechanism comprising a manual control duct and a pedal control duct; and means for opening and closing the control ducts and the tone ducts, said selective mechanism including means for preventing the sounding of any given tone element in one series when the corresponding element in the other series is sounding at the time the first mentioned element tends to come into action.

8. A record-controlled musical instrument comprising, in combination, a series of tone-emitting elements producing manual effects, a series of elements producing pedal effects, a series of tone-ducts common to the elements of each of said series, a movable controlling device for said tone ducts, and a series of pneumatic switches controlled by the controlling device and movable to connect any one or more of the elements of one of the series of tone-emitting elements and any one or more of the elements of the other of said series to the corresponding common tone ducts independently of every other element of both of said series of tone-emitting elements.

9. A record-controlled musical instrument comprising, in combination, a series of tone-emitting elements producing manual effects, a series of tone-emitting elements producing pedal effects, operating pneumatics for each of the elements of each series, a series of tone-ducts, each tone-duct being common to one element in each of the series of tone-emitting elements, pneumatic switches the position of which controls the operating pneumatics, control ducts for said switches and a movable operating member which controls both the tone ducts and the control ducts.

10. A record-controlled musical instrument comprising, in combination, two series of tone-emitting elements, a series of tone ducts common thereto, a control duct, selecting mechanism controlled by said control duct for bringing any one or more of the elements of one of the series of tone-emitting elements and any one or more of the elements of the other of said series into communication with the tone ducts at one time independently of every other element of

both of said series, and operating means for opening and closing the tone ducts and the control duct, said selecting mechanism being constructed to respond only to those tone ducts which are opened at the moment the control ducts are being closed.

11. A record-controlled musical instrument comprising, in combination, a series of tone-emitting elements producing manual effects, a series of tone-emitting elements producing pedal effects, a series of tone ducts each of which is common to an element in each of the aforesaid series of tone emitting elements, a pedal control duct, a manual control duct, a selecting mechanism coöperatively related to and controlled by the opening and closing of said control ducts and an operating member for opening and closing both the control ducts and the tone ducts, said selecting mechanism being arranged to respond only to the tone ducts which are opened as one of the control ducts is closed.

12. A record-controlled musical instrument comprising, in combination, a series of tone-emitting elements producing manual effects, a series of tone-emitting elements producing pedal effects, a series of tone ducts each of which is common to one element in each of the two series of tone-emitting elements, a selective mechanism embodying a series of primary control pneumatics, a series of pneumatic switches controlled by said primary pneumatics, and a series of operating pneumatics for the tone-emitting elements controlled by said pneumatic switches.

13. A record-controlled musical instrument comprising, in combination, a series of tone-emitting elements producing manual effects, a series of tone-emitting elements producing pedal effects and a common selecting mechanism coöperatively related to said elements embodying a source of power and means for bringing any one or more of the elements of one of said series of tone-emitting elements and any one or more of the elements of the other of said series into communication with said source of power independently of every other element of both of said series.

14. A record-controlled musical instrument comprising, in combination, a series of tone-emitting elements producing manual effects, a series of tone-emitting elements producing pedal effects, a common selecting mechanism coöperatively related to said elements, tone ducts the opening of which determines which of the elements of a series shall sound and control ducts the condition of which determines which series shall sound.

15. A record-controlled musical instrument comprising, in combination, a series of tone-emitting elements producing manual effects, a series of tone-emitting elements producing pedal effects, a common selecting

mechanism coöperatively related to said elements, tone ducts the opening of which determines which of the elements of a series shall sound and control ducts the condition of which determines which series shall sound 70 and a common controlling element for said ducts.

16. A record-controlled musical instrument comprising, in combination, a plurality of series of tone-emitting elements, a 75 series of operating pneumatics for each series of tone-emitting elements, a plurality of control pneumatics, and a series of pneumatic switches disposed between the control pneumatics and the operating pneumatics, 80 said switches being controlled by said control pneumatics and in turn controlling said operating pneumatics.

17. In a record-controlled musical instrument, the combination with a plurality of 85 tone-emitting elements and a plurality of operating pneumatics therefor, respectively, of a tone duct common to both operating pneumatics, connections between the tone-duct and the respective operating pneumatics, pneumatically-operable means for opening or closing said connections, and means for variably controlling and applying the forces which operate the opening and closing means, the said controlling and applying means applying the pneumatic forces to the opening and closing means in such manner as to hold the opening and closing means against change of position while the duct is open.

18. In a record-controlled musical instrument, the combination with a plurality of tone-pneumatics and a plurality of operating pneumatics therefor, respectively, of a tone-duct common to both operating pneumatics, connections between the tone-duct and the respective operating pneumatics, said connections including a tone pneumatic to which the tone duct is connected, pneumatically operable means between the tone-pneumatic and respective operating pneumatics for opening or closing the ways between the same, and means for variably controlling and applying the forces which operate the opening and closing means, the said controlling and applying means applying the pneumatic forces to the opening and closing means in such a manner as to hold the opening and closing means against change of position while the tone duct is open.

19. In a record-controlled musical instrument, the combination with a plurality of tone-emitting elements and a plurality of operating pneumatics therefor, respectively, of a tone-duct common to both operating pneumatics, connections between the tone-duct and the respective operating pneumatics, pneumatically-operable valves having membranes, said valves opening or closing said connections, and means whereby the 130

forces which operate the membranes of said valves are variably controlled and applied, the said means being so correlated with the membranes that the valves may be moved 5 under control thereof and when so moved the tendency on the opening of the tone duct will be to hold the valves against change of position while the duct is open.

20. In a record-controlled musical instrument, the combination with a plurality of tone-emitting elements and a plurality of operating pneumatics therefor, respectively, of a tone-duct common to both operating pneumatics, connections between the tone-duct and the respective operating pneumatics, including a tone-pneumatic to which the tone-duct is connected, pneumatically-operable valves having membranes, said valves opening or closing the ways between 10 the tone-pneumatic and the respective operating pneumatics, and means whereby the forces which operate the membranes of said valves are variably controlled and applied, the said means being so correlated with the 15 tone-pneumatic and membranes that the valves may be moved under control thereof and when so moved the tendency on the opening of the tone duct will be to hold the valves against change of position while the 20 duct is open.

21. In a record-controlled musical instrument, the combination with a plurality of tone-emitting elements and a plurality of operating pneumatics therefor, respectively, of a tone-duct common to both operating pneumatics, connections between the tone-duct and the respective operating pneumatics, said connections having ports which 25 respectively communicate with the operating pneumatics, the connections also including a tone pneumatic between the ports and the tone-duct and each port being further in communication with a source of supply of air of different pressure from that which flows 30 therethrough between the tone pneumatic and the operating pneumatics, independently operable valves for opening and closing communication of the ports alternately with the tone pneumatic and with said source 35 of supply of air of different pressure, pneumatically operable controllers and connections between the controllers and valves for variably applying the forces which operate 40 the valves and holding the valves against change of position while the tone-duct is 45 open.

22. In a record-controlled musical instrument, the combination with a plurality of tone-emitting elements and a plurality of operating pneumatics therefor, respectively, of a tone-duct common to both operating pneumatics, connections between the tone-duct and the respective operating pneumatics, said connections including a tone-pneumatic, a chamber in communication with the 50

tone-pneumatic and having ports which communicate with the respective operating pneumatics, the ports being also arranged to have communication with a source of air supply, independently operable means for 55 opening or closing communication of the ports with said chamber or said source of air supply, alternately, said means having pneumatically operable elements, and means for variably controlling and supplying the 60 air forces to the pneumatically operable elements, the controlling and applying means for said forces being so correlated with said elements that the latter may be adjusted under control thereof and when so adjusted 65 the tendency on the opening of the tone-duct will be to maintain them against change of position while the duct is open.

23. In a record-controlled musical instrument, the combination with a plurality of 70 series of tone-emitting elements and a plurality of series of operating pneumatics therefor respectively, of a series of tone ducts common to both series of operating pneumatics, and mechanism for selectively 75 controlling the communication of the tone ducts with the operating pneumatics, automatically, the said mechanism including control ducts, a plurality of series of valves in the connections between the series of tone 80 ducts and the respective series of operating pneumatics, every valve of either series being operable independently of every other valve of the same or different series to open 85 or close the passages from the tone ducts to the operating pneumatics and means connected with the control ducts and operated under control thereof for operating said 90 valves, and means for opening and closing the tone ducts and control ducts. 95

24. In a record-controlled musical instrument, the combination with a plurality of 100 series of tone-emitting elements and a plurality of series of operating pneumatics therefor, respectively, of mechanism for operating any one or more of the operating pneumatics of either series alone or of both 105 series in a multiplicity of combinations, at will, from a set of tone apertures common to both series of operating pneumatics, the 110 said mechanism including a tracker having a series of tone apertures each of which is common to corresponding pneumatics of the series of operating pneumatics, the said tracker also having a plurality of control 115 apertures, connections between the tone apertures and the series of operating pneumatics, said connections including valves, means connected with the control apertures for operating said valves, and a record having perforations to register with tone-apertures in the tracker and other perforations to register with the control apertures in said tracker. 120

25. In a record-controlled musical instrument, the combination with a plurality of 125

- series of tone-emitting elements and a plurality of series of operating pneumatics therefor, respectively, of mechanism for operating any one or more of the operating pneumatics of either series alone or of both series in a multiplicity of combinations, at will, from a set of apertures common to both series of operating pneumatics, the said mechanism including a tracker having a series of tone apertures each of which is common to corresponding pneumatics of the series of operating pneumatics, the said tracker also having a pair of control apertures, connections between the tone apertures and the series of operating pneumatics, means having connection with the control apertures and controlled by the opening and closing thereof for opening and closing the ways from the tone-apertures to the operating pneumatics, and a record having note perforations and control perforations, the note perforations registering with the tone apertures of the tracker and the control perforations registering with the control apertures of the tracker and being arranged with their rear ends substantially in line transversely of the music roll with the particular note apertures related to operating pneumatics which are to be coupled.
26. In a record-controlled musical instrument, the combination with a plurality of series of tone-emitting elements and a plurality of series of operating pneumatics having connection therewith, of a series of tone ducts common to the plurality of series of operating pneumatics, connections between the tone ducts and the operating pneumatics, said connections including a series of pneumatic switches, each switch having pneumatically operable valves which respectively control communication of the switch with corresponding pneumatics of the series of operating pneumatics, said valves being so arranged that the connections to one series of operating pneumatics are normally open and the connections to the other series of operating pneumatics are normally closed, and means for moving said valves.
27. In a record-controlled musical instrument, the combination with a plurality of series of tone-emitting elements and a plurality of series of operating pneumatics having connection therewith, of a series of tone ducts common to the series of operating pneumatics, connections between the tone ducts and the operating pneumatics, said connections including a series of pneumatic switches, each switch having pneumatically operable valves which control communication of a tone duct with corresponding pneumatics of the series of operating pneumatics, the series of pneumatic switches also having passages for airs of different pressures, one of said passages be-
- ing common to the series of valves which control the passages to one series of operating pneumatics and another being common to the series of valves which control the passages to another series of operating pneumatics, and means for controlling the wind passages.
28. In a record-controlled musical instrument, the combination with a plurality of series of tone-emitting elements and a plurality of series of operating pneumatics having connection therewith, of a series of tone ducts common to the series of operating pneumatics, connections between the tone ducts and the operating pneumatics, said connections including a series of pneumatic switches, each switch having pneumatically operable valves which control communication of a tone duct with corresponding pneumatics of the series of operating pneumatics, the series of pneumatic switches also having passages for airs of different pressures, one of said passage being common to the series of valves which control the passages to one series of operating pneumatics and another being common to the series of valves which control the passages to another series of operating pneumatics, and means for controlling the wind passages, the latter means including a pair of control ducts and control pneumatics having connection with said ducts and with said passages of the switches.
29. In a record-controlled musical instrument, the combination with a plurality of tone-emitting elements and a plurality of operating pneumatics therefor, respectively, of means for selectively operating the operating pneumatics comprising a tone-duct common to both operating pneumatics, connections between the tone-duct and the respective operating pneumatics, said connections including valves to open or close communication between the tone-duct and the respective operating pneumatics, and controllers for moving the valves independently of each other to cause the operation of either operating pneumatic alone, or of both together, at will, when the tone duct is opened.
30. In a record-controlled musical instrument, the combination with a plurality of tone-emitting elements and a plurality of operating pneumatics therefor, respectively, of mechanism for selectively operating the operating pneumatics, the said mechanism comprising a common tone duct, a tone-pneumatic having connection with the duct, means between and connected with the tone pneumatic and respective operating pneumatics, forming passages for air of different pressures, valves for said passages, and pneumatically operable controlling means for moving said valves automatically.
31. In a record-controlled musical instrument, the combination with a plurality of

tone-emitting elements and a plurality of operating pneumatics therefor, respectively, each operating pneumatic having a collapsible and expansible element and means 5 through which fluid is supplied to or withdrawn from said element to expand it or cause it to collapse, said means including a valve for controlling the fluid and a pressure-operated member for operating the 10 valve, in combination with a tone duct common to both operating pneumatics, connections between the tone-duct and the respective operating pneumatics, said connections including valves, and controllers for moving 15 the valves to cause the operation of either operating pneumatic alone or both together, at will, when the tone duct is opened.

32. In a record-controlled musical instrument, the combination with a plurality of tone-emitting elements and a plurality of operating pneumatics therefor, respectively, of a tone-duct common to both operating pneumatics, connections between the tone 25 duct and the respective operating pneumatics, said connection including a pneumatic switch having valves, and pneumatically operable controllers for automatically moving the valves of the pneumatic switch to 30 cause the operation of either operating pneumatic alone, or both together, at will, when the tone-duct is opened.

33. In a record-controlled musical instrument, the combination with a plurality of tone-emitting elements and a plurality of operating pneumatics therefor, respectively, of a common tone-duct, a tone-pneumatic having connection with the duct, a pneumatic switch having members for the operating pneumatics respectively, means connecting the pneumatic switch with the tone pneumatic, the switch member having ports which are arranged to have communication 35 with the tone pneumatic and the atmosphere, alternately, and including valves for controlling such communication, and means for automatically moving the valves independently of each other.

34. In a record-controlled musical instrument, the combination with a plurality of tone-emitting elements and a plurality of operating pneumatics therefor, respectively, of means for selectively operating the operating pneumatics comprising a common tone 50 duct, a tone pneumatic having a chamber and valved openings through which said chamber is supplied with air at different pressures, the tone pneumatic also having connection with the tone duct and including 55 means whereby its valve is operated by the opening and closing of the tone-duct, valved switch members having connection with the respective operating pneumatics and with said chamber of the tone-pneumatic, and means for moving the valves of 60

the switch members to establish or cut off communication of either or both operating pneumatics with the tone-pneumatic.

35. In a record-controlled musical instrument, the combination with a plurality of tone-emitting elements and a plurality of operating pneumatics therefor, respectively, of a tone-duct common to both operating pneumatics, a tone-pneumatic having connection with the tone-duct and provided 70 with a chamber for air of different pressures and a means for alternately opening said chamber to and closing it against the sources of air of different pressures, respectively, said means being controlled by the 75 opening and closing of the tone duct, a switch having a chamber in communication with said chamber of the tone-pneumatic and provided with ports which have communication with the respective operating 80 pneumatics and are so arranged that the latter will be alternately subjected to airs of different pressures one of which is from said chamber of the switch, and independently operable means for opening and closing 85 said ports, said means including pneumatically operable elements and means whereby the forces which operate said elements are variably controlled and applied to move the opening and closing means and 90 maintain them against change of position while a tone-duct is open.

36. In a record-controlled musical instrument, the combination with a plurality of tone-emitting elements and a plurality of operating pneumatics therefor, respectively, of a tone-duct common to both operating pneumatics, a tone-pneumatic having connection with the tone-duct and provided 100 with a chamber for air of different pressures and means for alternately opening said chamber to and closing it against the sources of air of different pressures, respectively, said means being controlled by the opening and closing of the tone duct, a switch having a chamber in communication with said chamber of the tone-pneumatic and provided with ports which have communication with the respective operating 105 pneumatics and are so arranged that the latter will be alternately subjected to airs of different pressures one of which is from said chamber of the switch, the switch also having independently operable means for opening and closing said ports, said means including pneumatically operable elements, and control pneumatics for selectively controlling the forces which operate said means.

37. In a record-controlled musical instrument, the combination with a plurality of tone-emitting elements and a plurality of operating pneumatics therefor, respectively, of means for selectively operating the operating pneumatics comprising a tone-duct common to both operating pneumatics, op- 125

erative connections disposed between the tone-duct and the respective operating pneumatics, said connections including valves, and pneumatically-operated valved controllers which control the valves of the connections independently of each other.

38. In a record-controlled musical instrument, the combination with a plurality of tone-emitting elements and a plurality of operating pneumatics therefor, respectively, of means for selectively operating the operating pneumatics comprising a tone-duct common to both operating pneumatics, operative connections disposed between the tone-duct and the respective operating pneumatics, said connections including valves, and primary and secondary controllers which control the valves of the connections independently of each other.

39. In a record-controlled musical instrument, operating pneumatics and a chest having a chamber provided with ports for the respective operating pneumatics, the ports opening to the chamber and to a source of air other than through the chamber, valves for the ports; said chest also having a pair of chambers on opposite sides of each port, flexible membranes between the first mentioned chamber and one chamber of each of the said pairs, and other flexible membranes in the other chambers of the said pairs, the valves having stems to which the membranes are connected, the chest also having channels by which the chambers of each pair are connected with each other and with the ports, and further having chambers on the sides of the last mentioned membranes opposite the previously mentioned chambers.

40. In a record-controlled musical instrument, operating pneumatics and a chest having a chamber provided with ports for the respective operating pneumatics, the ports opening to the chamber and to a source of air other than through the chamber, a pair of valves for each port, said valves being mounted on a common stem and one of each pair closing the port against the chamber and the other against the separate source of air; said chest also having a pair of chambers on opposite sides of each port, flexible membranes between the first mentioned chamber and one chamber of each of the said pairs and other flexible membranes in the other chambers of said pairs, said membranes being connected to the ends of the valve stems, the chest also having channels by which the chambers of each pair are connected with each other and with the ports, and further having chambers on the sides of the last mentioned membranes opposite the previously mentioned chambers.

41. In a record-controlled musical instrument, operating pneumatics and a chest having a chamber provided with ports for the respective operating pneumatics, the ports

opening to the chamber and to a source of air other than through the chamber, valves for the ports; said chest also having a pair of chambers on opposite sides of each port, flexible membranes between the first mentioned chamber and one chamber of each of the said pairs and other flexible membranes in the other chambers of said pairs, the valves having stems to which the membranes are connected, the chest also having channels by which the chambers of each pair are connected with each other and with the ports, and further having chambers on the sides of the last mentioned membranes opposite the previously mentioned chambers, control pneumatics respectively connected with the last-mentioned chambers, and a tone pneumatic connected with the first-mentioned chamber.

42. In a record-controlled musical instrument, operating pneumatics and a chest having a chamber provided with ports for the respective operating pneumatics, the ports opening to the chamber and to a source of air other than through the chamber, valves for the ports; said chest also having a pair of chambers on opposite sides of each port, flexible membranes between the first-mentioned chamber and one chamber of each of the said pairs and other flexible membranes in the other chambers of said pairs, the valves having stems to which the membranes are connected, the chest also having channels by which the chambers of each pair are connected with each other and with the ports, and further having chambers on the sides of the last mentioned membranes opposite the previously mentioned chambers, primary control pneumatics, secondary control pneumatics connected to the primary control pneumatics, connections between the secondary control pneumatics and the last mentioned chambers, and a tone pneumatic connected with the first mentioned chamber.

43. In a record-controlled musical instrument, the combination with a plurality of tone-emitting elements and a plurality of operating pneumatics therefor, respectively, of a tone duct common to both operating pneumatics, a tone pneumatic having connection with the tone-duct and provided with a chamber having ports through which it is supplied with air of different pressures, and a valve for opening and closing these ports alternately, said valve being controlled by the opening and closing of the tone-duct, a chest having a chamber which is in communication with said chamber of the tone pneumatic and has ports extending from the chamber to a source of supply of air separate from the chamber, the chest further having a pair of chambers arranged on opposite sides of each port and additional chambers respectively associated with said pairs of chambers, means connecting the

chambers of the respective pairs with each other and with the ports and for connecting the ports with the respective operating pneumatics, independently-operable means 5 for opening and closing communication of the respective ports with the first-mentioned chamber of the chest and said separate source of supply of air alternately, said means including pneumatically-operable elements, 10 certain of which are subjected to the forces in said first-mentioned chamber of the chest and one chamber of each pair, and others of which elements are subjected to the forces in the other chamber of each pair and in 15 said additional chambers associated therewith, and means whereby said additional chambers are opened to air of respectively different pressures, at will.

44. In a record-controlled musical instrument, the combination with a plurality of tone-emitting elements and a plurality of operating pneumatics therefor, respectively, of a tone-duct common to both operating pneumatics, a tone pneumatic having connection 20 with the tone duct and provided with a chamber having ports through which it is supplied with air of different pressures, and a valve for opening and closing these ports alternately, said valve being controlled by the 25 opening and closing of the tone duct, a chest having a chamber which is in communication with said chamber of the tone pneumatic and has ports extending from the chamber to a source of supply of air 30 separate from the chamber, the chest further having a pair of chambers on opposite sides of each port and additional chambers respectively connected with said pairs of 35 chambers, means connecting the chambers of the respective pairs with each other and with the ports and for connecting the ports with the respective operating pneumatics, independently operable means for opening 40 and closing communication of the respective ports with the first mentioned chamber of the chest and said separate source of supply of air, alternately, said means including pneumatically operable elements, 45 certain of which are subjected to the forces in said first-mentioned chamber of the chest and one chamber of each pair, and others of which elements are subjected to the forces in the other chamber of each pair and in 50 said additional chambers connected therewith, and means whereby said additional chambers are opened to air of respectively different pressures, at will, said means including primary and secondary control 55 pneumatics having chambers for air of relatively different pressures, said chambers having valves, special control ducts, means whereby the valves of the primary control pneumatics are operated by the opening and 60 closing of the control ducts, means whereby the valves of the secondary control pneumatics are operated under control of the air in said chambers of the primary control pneumatics and means whereby said chambers of the secondary control pneumatics are connected with said additional chambers of the chest respectively.

55

60

ling the entrance of air to the chambers of the control pneumatics and special ducts for controlling the operation of the valves. 65

45. In a record-controlled musical instrument, the combination with a plurality of tone-emitting elements and a plurality of operating pneumatics therefor, respectively, of a tone-duct common to both operating pneumatics, a tone pneumatic having connection with the tone duct and provided with a chamber having ports through which it is supplied with air of different pressures, and a valve for opening and closing these 70 ports alternately, said valve being controlled by the opening and closing of the tone duct, a chest having a chamber which is in communication with said chamber of the tone pneumatic and has ports extending from the 75 chamber to a source of supply of air separate from the chamber, the chest further having a pair of chambers on opposite sides of each port and additional chambers respectively connected with said pairs of 80 chambers, means connecting the chambers of the respective pairs with each other and with the ports and for connecting the ports with the respective operating pneumatics, independently operable means for opening 85 and closing communication of the respective ports with the first mentioned chamber of the chest and said separate source of supply of air, alternately, said means including pneumatically operable elements, 90 certain of which are subjected to the forces in said first-mentioned chamber of the chest and one chamber of each pair, and others of which elements are subjected to the forces in the other chamber of each pair and in 95 said additional chambers connected therewith, and means whereby said additional chambers are opened to air of respectively different pressures, at will, said means including primary and secondary control 100 pneumatics having chambers for air of relatively different pressures, said chambers having valves, special control ducts, means whereby the valves of the primary control pneumatics are operated by the opening and 105 closing of the control ducts, means whereby the valves of the secondary control pneumatics are operated under control of the air in said chambers of the primary control pneumatics and means whereby said chambers of the secondary control pneumatics are connected with said additional chambers of the chest respectively. 110
